UNITED STATES PATENT OFFICE.

REA P. WRIGHT, OF WASHINGTON, DISTRICT OF COLUMBIA, ASSIGNOR TO JOHN FRANCIS HEMENWAY, OF NEW YORK, N. Y.

AUTOMATIC PRESSURE-ROLL-RELEASING DEVICE FOR CLOTHES-WRINGERS.

1,220,048.

Specification of Letters Patent. Patented Mar. 20, 1917.

Application filed October 26, 1916. Serial No. 127,900.

To all whom it may concern:

Be it known that I, REA P. WRIGHT, a citizen of the United States, residing at Washington, in the District of Columbia, have invented certain new and useful Improvements in Automatic Pressure-Roll-Releasing Devices for Clothes-Wringers, of which the following is a specification, reference being had therein to the accompanying drawing.

This invention relates to certain new and useful improvements in automatic pressure roll releasing devices for clothes wringers, and the object of the invention is to simplify the construction of the release by providing the top bar of the wringer frame with slidably mounted internally threaded boxes for the pressure screws in connection with means for holding said boxes in predetermined position within the top bar in such a manner that the boxes will be instantaneously released on the separation of the pressure rolls.

Another object of the invention is to provide a construction of release which can be readily applied to an ordinary construction of wringer, the parts of the release being mounted on the frame of the wringer in such a manner that it can be readily applied.

Other and further objects and advantages of the invention will be hereinafter set forth and the novel features thereof defined by the appended claims.

In the drawings,

Figure 1 is a side elevation partly in section of a clothes wringer showing the application of my improved construction of pressure release thereto;

Fig. 2 is a detail perspective view of a slidably mounted internally threaded box and a bearing sleeve thereto;

Fig. 3 is a detail vertical section through a slightly modified form; and

Fig. 4 is a detail view of a slightly modified form of bearing having an extension provided with a bevel portion for operating the pivoted latch.

Like numerals of reference refer to like parts in the several figures of the drawing.

In the drawing, 1 indicates a wringer frame having slotted side bars 2 in which are mounted superposed pressure rolls 3 and 4 carried by shafts 5 and 6 which are mounted in bearings arranged within the

slotted side bars 2, the upper bearings being provided with spring supports 7 carrying pressure springs 8 engaged by bearing plates 9 carried by a pressure bar 10.

Secured within the slotted side bars 2 at their upper ends is a top bar 11 which is provided with a vertical bore adjacent each end in which a tapering bearing sleeve 12 is adapted to be driven from the under side, said bearing sleeve having oppositely disposed grooves 13 adapted to receive the oppositely disposed ribs 14 of an internally threaded box 15 in order to allow the box to slide within the bearing without rotating therein, said box having a lateral projecting lug 16 at its lower end working in a slot 17 formed in the bearing sleeve 12 for limiting the upward movement of the internally threaded box for the purpose hereinafter described. Mounted within the threaded boxes 15 are pressure screws 18 adapted to engage the bearing plates 9 for adjusting the pressure on the pressure rolls.

Pivottally mounted on the side bars 2 of the wringer frame are latches 19 having hook portions 20 at their upper ends extending over the top bar above the movable boxes 15 so as to hold said boxes in predetermined position within the top bar. The pivoted latches 19 are provided with tail portions 21 working in guideways 22 carried by the side bars, the lower ends of said tail portions 21 carrying adjustable trip members 23 arranged above conical members 24 carried by the ends of the shaft 90 of the upper pressure roll 4 so that when the upper pressure roll 4 is moved away from the lower pressure roll 3, by a foreign object passing between the rolls, the conical members will engage the adjustable trip members 23 and rock the latches 19 on their pivots in order to move the hook portions from off of the boxes 15 which allows the boxes to move vertically within the top bar so that the pressure screws will be moved away from the bearing 9 so as to release the pressure on the pressure rolls.

In the modification shown in Fig. 3, the top bar 25 is provided with a vertical bore in which is slidably mounted an internally threaded box 26 having a groove 27 into which extends a plate 28 for limiting the upward movement of the box within the bore of the top bar and for preventing the same from rotating as the pressure screw 110

is adjusted. The end of the top bar is provided with a horizontally disposed opening communicating with the vertical bore of the top bar and through which extends the 5 hook portion 29, of a pivoted latch 30, carried by the side bar of the wringer frame, said hook portion being adapted to extend into a notch 31 formed in the outer wall of the box 26, so as to hold said box in 10 predetermined position within the wringer frame in order to enable the pressure screws to be adjusted in the ordinary manner.

By this construction I provide the top bar with a vertical bore in which the 15 threaded box is slidably mounted with a horizontally disposed opening communicating with said bore through which the hook of the pivoted latch extends and is seated in a notch in the box so as to hold the box 20 in such a manner that when the latch is moved by the separation of the pressure rolls, the box will be released so as to release the pressure means.

In Fig. 4 I have shown an upper bearing 25 32 of the pressure roll shaft having an extension provided with a beveled face 23 which is adapted to coöperate with the trip member of the latch so as to rock the latch on its pivot in order to release the pressure 30 screw carrying boxes.

From the foregoing description it will be seen that I have provided a clothes wringer with slidably mounted pressure screw carrying boxes which are released by the separation 35 of the pressure rolls.

I claim:

1. A clothes wringer, comprising a frame having pressure rolls and pressure means for said rolls, vertically movable internally 40 threaded pressure screw carrying boxes mounted in said frame carrying pressure screws for adjusting said pressure means, movable members for holding said boxes in predetermined position within said frame, 45 and means actuated by the separation of said pressure rolls for shifting said movable members out of engagement with said boxes for releasing said pressure means.

2. A clothes wringer, comprising a frame 50 having pressure rolls and pressure means for said rolls, said frame having a top bar, internally threaded non-rotatable boxes slidably mounted in said top bar carrying pressure screws for adjusting said pressure means, pivoted latches for holding said boxes in predetermined position within said top bar, and members having beveled faces actuated by the separation of said pressure 55 rolls engaging said latches for moving said latches out of engagement with said boxes for releasing said pressure means.

3. A clothes wringer, comprising a frame having pressure rolls and pressure means for said rolls mounted therein, a top bar 60 fixed in said frame, slidably mounted non-

rotatable internally threaded boxes carried by said top bar, pressure screws carried by said boxes for adjusting said pressure means, pivoted latches carried by the frame of said wringer for holding said boxes in predetermined position within said top bar, 70 adjustable trip members carried by said latches, and members actuated by the separation of said rolls having inclined faces engaging said adjustable trip members for releasing said boxes. 75

4. A clothes wringer, comprising a frame having pressure rolls and pressure means for said rolls mounted therein, a top bar fixed in said frame, slidably mounted non-rotatable internally threaded boxes carried by said top bar, pressure screws mounted in 80 said boxes for adjusting said pressure means, pivoted latches carried by the frame of said wringer engaging said boxes for holding said boxes in predetermined position within said top bar, and conical members 85 engaging said latches on the separation of said rolls for moving said latches out of engagement with said boxes for releasing 90 said pressure means.

5. A clothes wringer, comprising a frame having pressure rolls and pressure means for said rolls mounted therein, a top bar fixed in said frame, non-rotatable slidably 95 mounted internally threaded boxes carried by said top bar, means for limiting the movement of said boxes within said top bar, pivoted latches carried by the side bars of said frame engaging said boxes for holding 100 said boxes in predetermined position within said top bar, and members having beveled faces engaging said latches on the separation of said rolls for moving said latches out of engagement with said boxes for releasing 105 said pressure means.

6. A clothes wringer, comprising a frame having pressure rolls and pressure means for said rolls mounted therein, bearing sleeves mounted in the frame of said 110 wringer, non-rotatable sliding boxes mounted in said bearing sleeves, pressure screws carried by said boxes for adjusting said pressure means, means for limiting the movement of said boxes within said bearing, pivoted latches carried by the frame of said wringer for holding said boxes in predetermined position therein, adjustable trip members carried by said latches, and conical members carried by the shaft of one 115 of said pressure rolls coöperating with said trip members on the separation of said rolls for releasing said pressure means. 120

7. A clothes wringer, comprising a frame having pressure rolls and pressure means 125 for said rolls, vertically moving boxes mounted in said frame carrying means for adjusting said pressure means, movable members for holding said boxes in predetermined position within said frame, and means 130

actuated by the abnormal separation of said pressure rolls for shifting said movable members out of engagement with said boxes for releasing said pressure means.

- 5 8. A clothes wringer, comprising a frame having pressure rolls and pressure means for said rolls mounted therein, bearing sleeves fixed in said frame having slotted walls, internally threaded boxes slidably 50 mounted within said bearing sleeves having lugs projecting within the slots thereof, pivoted latches mounted on the side bars of said frame engaging said boxes, pressure screws mounted in said boxes for adjusting 55 said pressure means, and members engaging said latches on the abnormal separation of said rolls for moving said latches out of engagement with said boxes for releasing said pressure means.
- 10 9. A clothes wringer, comprising a frame having pressure rolls and pressure means for said rolls mounted therein, a top bar fixed in said frame, bearing sleeves secured in said top bar adjacent each end having 60 slotted side walls and provided with oppositely disposed grooves, internally threaded boxes having oppositely disposed ribs slidably mounted in said bearing sleeves, lugs 65 projecting from said boxes extending into the slots of said sleeves, pressure screws mounted in said boxes for adjusting said pressure means, means for holding said boxes in position within said bearing sleeves, and means actuated by the abnormal separation 70 of said rolls for actuating said retaining means for releasing said pressure means.
- 15 10. A clothes wringer, comprising a frame having pressure rolls and pressure means for said rolls mounted therein, a top bar fixed 75 in said frame having bearing sleeves at its ends, internally threaded boxes mounted in said bearing sleeves, means for limiting the movement of said boxes within said bearing sleeves, pivoted latches carried by the side 80 bars of said frame having hooked portions 85 means.

extending over the upper edge of said boxes, adjustable trip members carried by said latches, and conical members carried by the shaft of the upper pressure roll coöoperating with said trip members on the vertical movement of said pressure roll for moving said latches out of the path of said boxes for releasing said pressure means.

11. A clothes wringer, comprising a frame having pressure rolls and pressure means for said rolls mounted therein, a top bar fixed in said frame having vertical bores adjacent each end, bearing sleeves fixed in said bores having vertical slots, internally threaded boxes slidably mounted in said bearing sleeves having lugs extending into the slots thereof, latches pivotally mounted on the side bars of said frame having hooked portions extending in the path of travel of said boxes, pressure screws mounted in said boxes for adjusting said pressure means, adjustable trip members carried by the tail portions of said latches, and members actuated by the abnormal separation of said pressure rolls coacting with said trip members for moving the hook portion of said latches out of the path of travel of said boxes for releasing said pressure means.

12. A clothes wringer, comprising a frame having pressure rolls and pressure means for said rolls, boxes movably mounted in said frame carrying means for adjusting said pressure means, means for limiting the movement of said boxes within said frame, movable members for holding said boxes in predetermined position within said frame, and means actuated by the abnormal separation of said pressure rolls for shifting said movable members out of engagement with said boxes for releasing said pressure means.

In testimony whereof I hereunto affix my signature.

REA P. WRIGHT.
